UNITED STATES PATENT OFFICE

CORBAN H. ZILER, OF CARTHAGE, MISSOURI, ASSIGNEE TO L. A. YOUNG SPRING AND WIRE CORPORATION, OF DETROIT, MICHIGAN

SPRING-NESTING MECHANISM FOR COILING MACHINES

Application filed February 6, 1929. Serial No. 337,758.

The main objects of this invention are:

First, to provide a mechanism adapted for use in combination with spring-coiling machines which automatically nests the 5 springs as they are delivered from the coiling machine.

Second, to provide a mechanism having these advantages which may be added as an attachment to coiling machines of a type now 10 very extensively used.

Third, to provide a nesting mechanism for coiling machines in which the parts are so constructed and arranged that the wear and strain thereon is relatively slight.

Fourth, to provide a mechanism which is 15 of large capacity and may be readily adjusted to the speed of the coiling machine.

Objects pertaining to details and economies of my invention will definitely appear 20 from the description to follow. The invention is defined in the claims.

A structure which embodies the features of my invention is clearly illustrated in the accompanying drawing in which:

Fig. 1 is a side elevation of a coiling machine embodying the features of my invention;

Fig. 2 is a fragmentary elevation looking from the right of Fig. 1, parts being shown 30 in vertical section;

Fig. 3 is a fragmentary perspective view of the nesting mechanism;

Fig. 4 is a detail view partially in vertical section showing further details of the 35 nesting mechanism; and

Fig. 5 is a detail view partially in section on the broken line 5—5 of Fig. 1.

In the accompanying drawing, 1 designates the coiling mechanism generally, and 40 as the details of this mechanism form no part of my present invention they are not described herein. It will be understood that my improvements are capable of embodiment in certain standard and extensively 45 used types of machine adapted for the coiling of helically coiled springs such as are employed in spring-seat cushions, beds, and the like.

The coiled springs 2 are projected trans- 50 versely from the coiling mechanism as they

are formed and are engaged by the transfer or nesting jaws 12 substantially simultaneously with the severing thereof from the stock from which they are formed indicated at 3.

The springs are projected over a segmentally curved support 4 which is pivoted on the rod 5 to swing from supporting position to allow the formed springs to be swung downwardly by the transfer or nesting jaws. 60 The support has a transverse slot 6 therein aligned with the jaws. A chute 7 is positioned to receive the formed springs, this chute having adjustable spring retaining members 8 mounted on its side walls. The 65 springs are delivered below these retaining members and pushed along thereunder as successive springs are delivered to the nesting chute as indicated in the drawings.

Transversely above this chute I mount a 70 shaft 9 having an arm 10 carrying a pivot 11 for the jaws 12 which have curved work-engaging portions 13 and terminate in the diverging tips 14. These jaws are not only free to swing on the pivot 11 but may move 75 axially thereon, being urged to work-engaging position by the springs 15. One of the jaws is provided with a spring guide member 16. Stops or thrust members 17 and 18 are mounted on one of the jaws to extend 80 across the space between the jaws, thereby limiting the movement of the springs into the jaws. A pusher arm 19 projects from one of the jaws to engage the side of the spring. 85

The jaws are opened by the wedge-shaped cam 20 with which they are engaged by a relatively rearward swinging movement. The cam 20 is carried by the arm 10.

To swing the jaws on their pivot in proper timed relation with the rotation of their supporting arm 10, I provide cams 21 and 22 which coact with the roller 23 on the link or pitman 24 pivoted at 25 to the jaws. This link or pitman is provided with a longitudinal slot 26 through which the shaft 9 is arranged, thereby slidably supporting the link. The cam 21 is shaped so as to swing the jaws forwardly with a quick movement to spring-engaging position, the jaws closing upon the 95

work as the roller passes over the point 27 of the cam. The work is carried forward by the jaws until it is delivered below the retaining members 8 and in nested relation to the springs previously delivered, the springs previously delivered being pushed along by the successive delivery of succeeding springs.

As the work reaches this delivery point the roller 23 comes into engagement with the cam 22. The engagement with this cam quickly moves the pitman or link 24 outward, moving the jaws backward on their pivot into engagement with the opening cam, thereby releasing the work in nested position.

To operate the support 4 in synchronism or proper timed relation to the jaws, I provide the shaft 9 with a cam 28 which acts upon the lever 29 pivoted at 30 and connected by the link 31 to an arm 32 on the support 4. The shaft 9 is connected by suitable gearing indicated at 33 to the driving gear 34 of the coiling machine. A spring 35 holds the lever 29 in engagement with the cam 28.

The springs are delivered by the nesting jaws to the spring-retaining members 8 which are mounted on the side walls of the chute 7, these members frictionally holding the spring so that as the successive springs are delivered, the coils of the spring delivered are pushed between the coils of the springs previously delivered, the delivery of successive springs pushing the previously delivered springs along in the holder and chute, with the result that they are very compactly nested.

My improved nesting mechanism very effectively and uniformly nests the coiled springs, is of large capacity, and may be readily adapted to the speed of the coiling machine. There is the further advantage that it is simple and compact in structure.

I have illustrated and described my improvements in an embodiment which I have found very satisfactory. I have not attempted to illustrate and describe various modifications and adaptations which I contemplate as I believe this disclosure will enable those skilled in the art to embody or adapt my improvements as may be desired.

Having thus described my invention what I claim as new and desire to secure by Letters Patent is:

1. The combination with a spring coiling means, of a segmental transversely slotted pivotally mounted support over which the springs are projected by said spring coiling means, a nesting chute provided with spaced spring retainers disposed longitudinally of the chute, a shaft mounted transversely above said chute and provided with an arm carrying a jaw pivot at its outer end, coacting jaws mounted on said pivot for rocking and lateral movement thereon, springs mounted on said pivot acting to close said jaws, a wedge-shaped cam on said arm and with which said jaws are engaged and disengaged by the

rocking movement of the jaws, a link slidably mounted on said shaft and pivotally connected to the outer ends of said jaws, said link being provided with a cam engaging roller, cams acting to reciprocate said link as the shaft is rotated thereby rocking said jaws on their pivot, said cams being positioned so that the jaws engage the springs in coiling position and release them after they are delivered to said nesting chute below said retainers, and means for actuating said spring support in synchronism with the actuation of said jaws comprising a pivoted lever, a cam on said shaft for actuating said lever, an arm on said support, and a link connecting said arm on said support to said lever. 70 75 80

2. The combination with a spring coiling means, of a segmental transversely slotted pivotally mounted support over which the springs are projected by said spring coiling means, a nesting chute provided with spaced spring retainers disposed longitudinally of the chute, a shaft mounted transversely above said chute and provided with an arm carrying a jaw pivot at its outer end, coacting jaws mounted on said pivot for rocking and lateral movement thereon, springs mounted on said pivot acting to close said jaws, a wedge-shaped cam on said arm and with which said jaws are engaged and disengaged by the rocking movement of the jaws, a link slidably mounted on said shaft and pivotally connected to the outer ends of said jaws, said link being provided with a cam engaging roller, cams acting to reciprocate said link as the shaft is rotated thereby rocking said jaws on their pivot, said cams being positioned so that the jaws engage the springs in coiling position and release them after they are delivered to said nesting chute below said retainers, and means for actuating said spring support in synchronism with the actuation of said jaws. 90 95 100 105 110

3. The combination of a nesting chute provided with spaced spring retainers disposed longitudinally of the chute, a shaft mounted transversely above said chute and provided with an arm carrying a jaw pivot at its outer end, coacting jaws mounted on said pivot for rocking and lateral movement thereon, springs mounted on said pivot acting to close said jaws, a wedge-shaped cam on said arm and with which said jaws are engaged and disengaged by the rocking movement of the jaws, a link slidably mounted on said shaft and pivotally connected to the outer ends of said jaws, said link being provided with a cam engaging roller, and cams acting to reciprocate said link as the shaft is rotated thereby rocking said jaws on their pivot, said cams being positioned so that the jaws engage the springs in coiling position and release them after they are delivered to said nesting chute below said retainers. 115 120 125 130

4. The combination of a nesting chute pro-

- vided with spaced spring retainers disposed longitudinally of the chute, a shaft mounted transversely above said chute and provided with an arm carrying a jaw pivot at its outer 5 end, coacting jaws mounted on said pivot for rocking and lateral movement thereon, springs mounted on said pivot acting to close said jaws, a wedge-shaped cam on said arm and with which said jaws are engaged and 10 disengaged by the rocking movement of the jaws, a link slidably mounted on said shaft and pivotally connected to the outer ends of said jaws, said link being provided with a cam engaging roller, cams acting to reciprocate said link as the shaft is rotated thereby rocking said jaws on their pivot, said cams being positioned so that the jaws engage the springs in coiling position and release them after they are delivered to said nesting chute 15 below said retainers, thrust members mounted on one of said jaws to overlap the other, and a pusher arm mounted on one of said jaws to project laterally therefrom.
5. The combination with a spring coiling 20 means, of a movably mounted support to which the springs are delivered by said spring coiling means, a nesting chute, a shaft provided with an arm, coacting jaws pivotally mounted on said arm for opening and closing and rocking movement, springs acting to close said jaws, a jaw opening cam on said arm and with which the jaws are engaged by the pivotal movement thereof, a link connected to said jaws and slidably supported 25 by said shaft, cams acting on said link as the shaft is rotated to reciprocate the same and thereby rock said jaws, a spring thrust member mounted on one of said jaws, a pusher arm projecting laterally from one of said 30 jaws to coact with a spring engaged by said jaws, and means for actuating said spring support in synchronism with said jaws.
6. The combination of a nesting chute, a shaft provided with an arm, coacting jaws 35 pivotally mounted on said arm for opening and closing and rocking movement, springs acting to close said jaws, a jaw opening cam on said arm and with which the jaws are engaged by the pivotal movement thereof, a link connected to said jaws and slidably supported by said shaft, cams acting on said link as the shaft is rotated to reciprocate the same and thereby rock said jaws, a spring thrust member mounted on one of said jaws, a pusher arm projecting laterally from one of said 40 jaws to coact with a spring engaged by said jaws, and means for actuating said spring support in synchronism with said jaws.
7. The combination with a spring coiling 45 means, of a movably mounted support to which the springs are delivered by said spring coiling means, a nesting chute, a shaft provided with an arm, coacting jaws pivotally mounted on said arm for opening and closing and rocking movement, springs acting to close said jaws, a jaw opening cam on said arm and with which the jaws are engaged by the pivotal movement thereof, a link connected to said jaws and slidably supported by said shaft, cams acting on said link as the shaft is rotated to reciprocate the same and thereby rock said jaws, a spring thrust member mounted on one of said jaws, a pusher arm projecting laterally from one of said 50 jaws to coact with a spring engaged by said jaws.
8. The combination of a nesting chute, a shaft provided with an arm, coacting jaws pivotally mounted on said arm for opening and closing and rocking movement, springs acting to close said jaws, a jaw opening cam on said arm and with which the jaws are engaged by the pivotal movement thereof, a link connected to said jaws and slidably supported by said shaft, cams acting on said link as the shaft is rotated to reciprocate the same and thereby rock said jaws, and means for actuating said spring support in synchronism with said jaws.
9. The combination with a spring coiling 55 means, of a pivoted support to which the springs are delivered by said coiling means, a nesting chute, transfer jaws acting to engage the springs while in coiling position and transferring the same to said chute, spring retaining members arranged in said chute, a spring pusher member movable with said jaws, and means for actuating said spring support synchronized with the said jaws so that the spring support is swung out of supporting position to permit the forward movement of the springs after engagement by the jaws.
10. The combination with a spring coiling 60 means, of a nesting chute, transfer jaws acting to engage an intermediate coil of the springs while in coiling position and transfer the same to said chute, spring retaining members arranged in and disposed laterally of said chute to coact with the ends of the springs, and a spring pusher member projecting transversely of and movable with said jaws.
11. The combination with a spring coiling 65 means, of a movable support positioned to support the springs delivered by said coiling means, a nesting chute, a rotatable support, jaws pivotally mounted on said support, means for rocking said jaws on their pivot as the support is revolved, a spring pusher member carried by said jaws, and means for actuating said spring support in synchronism with the opening and closing of said jaws.
12. The combination with a spring coiling 70 means, of a nesting chute, a rotatable support, jaws pivotally mounted on said support, means for rocking said jaws on their pivot as the support is revolved, and a spring pusher member carried by said jaws.
13. In a structure of the class described, 75 the combination of a nesting chute, a rotatable support, jaws pivotally mounted on said support, a cam means for swinging said jaws on their pivot brought into action by the rotation of said support, other cam means for 80

opening and closing said jaws brought into action by the swinging of said jaws on their pivot, and a pusher arm projecting laterally from one of said jaws to engage a spring engaged by the jaws.

5 14. In a structure of the class described, the combination of a nesting chute, a rotatable support, jaws pivotally mounted on said support, a cam means for swinging said jaws on their pivot brought into action by the rotation of said support, and other cam means for opening and closing said jaws brought into action by the swinging of said jaws on their pivot.

15 15. The combination with a spring coiling means, of a nesting chute, a rotatably mounted support, jaws pivotally mounted on said support, means for opening and closing said jaws brought into action by the swinging of the jaws on their pivot, and means for swinging said jaws on their pivot brought into action by the rotation of said arm.

In witness whereof I have hereunto set my hand.
